(57) **CLAIM**

The ornamental design for a jewelry cabinet, as shown and described.

DESCRIPTION

FIG. 1 is a front view of a jewelry cabinet showing my new design;

FIG. 2 is a rear view of the jewelry cabinet of FIG. 1; FIG. 3 is a left side view of the jewelry cabinet of FIG. 1; FIG. 4 is a right side view of the jewelry cabinet of FIG. 1; FIG. 5 is a top view of the jewelry cabinet of FIG. 1; FIG. 6 is a bottom view of the jewelry cabinet of FIG. 1; FIG. 7 is a front perspective view of the jewelry cabinet of FIG. 1;

FIG. 8 is a rear perspective view of the jewelry cabinet of FIG. 1;

FIG. 9 is another perspective view of the jewelry cabinet of FIG. 1, with a door of the jewelry cabinet in an open position; and,

FIG. 10 is an enlarged view of portion 10 in FIG. 9.

The broken lines encircling portions of the jewelry cabinet in FIG. 9 and illustrated in the enlarged view in FIG. 10 form no part of the claimed design.

1 Claim, 10 Drawing Sheets
